(57) CLAIM

The ornamental design for a shoe upper, as shown and described.

DESCRIPTION

FIG. 1 is a front perspective view of a shoe upper showing my new design;

FIG. 2 is a side view thereof;

FIG. 3 is a second side view thereof;

FIG. 4 is a toe end view thereof;

FIG. 5 is a heel end view thereof; and,

FIG. 6 is a top view thereof.

The broken line immediately adjacent to the bottom of the shaded area represents an unclaimed boundary of the design. The broken lines showing of the lace holding elements and the remainder of the shoe represent unclaimed subject matter and form no part of the claimed design.
